ATTORNEYS

UNITED STATES PATENT OFFICE.

LOUIS CHÈRIE HOULE, OF WEST PITTSBURG, PENNSYLVANIA.

GAME.

Application filed October 14, 1925. Serial No. 62,462.

To all whom it may concern:

Be it known that I, LOUIS C. HOULE, a citizen of the United States, and a resident of West Pittsburg, in the county of Lawrence and State of Pennsylvania, United States of America, have invented a new and Improved Game, of which the following is a full, clear, and exact description.

Objects of the present invention are to provide an amusing game apparatus which may be manufactured at a low cost, which is of simple, durable construction, and of neat and attractive appearance.

In a preferred embodiment, the game apparatus includes a target member which may be in the nature of a stake, and one or more projecting members for effecting the movement of projectiles toward the stake.

Preferably the projecting members are in the nature of catapults from which rings may be tossed at the stake.

With the above noted and other objects in view the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a plan view of a game apparatus embodying the invention.

Fig. 2 is a longitudinal sectional view on the line 2—2 of Fig. 1.

It is to be understood that while I have shown the invention embodied in an extremely simple form, the particular manner of constructing the apparatus is subject to a wide variety of modification and refinements.

As shown in the drawings, the apparatus includes a base member 10 which may conveniently consist of an elongated flat plate, either of wood or of some heavier material. Centrally of the plate there is mounted a field or platform 11 which has been illustrated as comprising a thin flat metallic

disc. A target member which in the present instance is a stake 12, rises from the center of the platform and is fixed in the plate. I provide a projecting or catapulting means which is used to throw projectiles preferably in the nature of rings 13. Any number of such projecting members might be used. In a preferred form of the apparatus however, I provide one of such members at each end of the plate 10, said members being in the nature of spring fingers 14 having their ends removably bolted or otherwise secured at 15 to the plate ends. The fingers 14 incline upwardly and outwardly from the plate and terminate in enlarged platform portions 16 disposed at a slight angle to the fingers.

In operation a ring 13 is placed upon one of the platforms 16 and said platform manually depressed by the finger of the player to approximately the dotted line position of Fig. 2. As such platform is released, the inherent resiliency of the spring fingers will tend to restore the same rapidly to its normal position, and the ring 13 will thereby be catapulted off the platform 16, describe a half circle in the air and land on or near the stake 12.

The use of the two catapulting members is convenient when two persons are playing the game. The game may be scored like quoits or in any other manner which is decided upon. The relatively wide platform member 11 assures a flat landing place for the rings even though the marksmanship of the players is relatively poor.

Various changes and alterations might be made in the form and arrangement of the parts described without departing from the invention, and hence I do not wish to limit myself to the precise details set forth, but shall consider myself at liberty to make such changes as fairly fall within the spirit and scope of the appended claims.

I claim:

1. A game apparatus including a base plate, a platform member of greater width than the base plate, arranged centrally

thereon, a stake rising from the center of the platform member, spring fingers having their ends fixed to the ends of the base plate, said fingers including enlarged free extremities for supporting annular projectile members whereby the projectile members may be catapulted toward the stake when the fingers are manually depressed and released.

2. In a game apparatus of the class de-

scribed, an elongated narrow base plate, a stake rising centrally therefrom, inclined spring fingers at opposite ends of the base adapted to support annular projectiles to be tossed at the stake, a symmetrical landing platform for the projectiles encircling the stake and extending laterally well beyond the base plate.

LOUIS CHÈRIE HOULE.
